Inventor.

F. Field

United States Patent Office.

FRANKLIN FIELD, OF TROY, NEW YORK.

Design No. 3,869, dated March 1, 1870.

DESIGN FOR A PAPER-COLLAR BOX.

The Schedule referred to in these Letters Patent and making part of the same.

To all whom it may concern:

Be it known that I, FRANKLIN FIELD, of the city of Troy, in the county of Rensselaer, and State of New York, have invented and produced a new and original Design for Boxes used in Packing Paper Collars and Cuffs, of which the following is a specification.

The nature of my design is fully represented in the accompanying drawings, to which reference is hereby made.

My design consists of a rectangular box, A, made of paper, paper and cloth, or other suitable material, and which may be of a cubical shape, or longer in one direction than the other, as I have shown it in the drawings.

At the top of this box is the lid B, which may be raised, and the box thereby opened, for the purpose of putting in or taking out collars or cuffs, as may be necessary.

In the front of the box is the loop or keeper d d.

The lid B is provided with a tongue, C, which passes through the loop or keeper d d, and presents the appearance shown in fig. 1, when the box is closed.

The object of my design is to produce a cheap and handsome packing-box for collars and cuffs, which will be a neat and tasteful article for a gentleman's toilet, while furnishing a convenient receptacle for his collars and cuffs in the package itself.

I claim as my invention—

The design for a packing-box for collars and cuffs, as shown and specified.

In witness whereof, I have hereunto set my hand this 8th day of February, 1870.

F. FIELD.
